UNITED STATES PATENT OFFICE.

GEORGE A. MOSHER, OF TROY, NEW YORK.

BUTTON-SETTING MACHINE.

SPECIFICATION forming part of Letters Patent No. 693,048, dated February 11, 1902

Application filed May 2, 1892. Renewed June 13, 1900. Serial No. 20,189. (No model.)

To all whom it may concern:

Be it known that I, GEORGE A. MOSHER, a citizen of the United States, residing at Troy, county of Rensselaer, and State of New York, have invented certain new and useful Improvements in Button-Setting Machines, of which the following is a specification.

My invention relates to such improvements; and it consists of the novel construction and combination of parts hereinafter described and subsequently claimed.

Reference may be had to the accompanying drawings, and the letters of reference marked thereon, which form a part of this specification.

Similar letters refer to similar parts in the several figures.

Figure 1 of the drawings is a view in side elevation of my improved machine with the cover or side plate removed to show the interior mechanism. The lower and intermediate portions of the supporting-standard are broken away. The position of the respective parts is that assumed when the machine is idle, a fastener being shown in the holding member in position to be set upon the fabric. Fig. 2 is a view similar to that shown in Fig. 1, the respective parts being shown in the position assumed when the machine has completed the operation of setting a fastener upon the fabric, also showing a central vertical longitudinal section of the stationary supply-chute. The standard is wholly broken away and some of the parts are removed to better show the remaining parts. Fig. 3 is a view in front elevation with the cover in place. Fig. 4 is a top plan view of the machine as shown in Fig. 3. Fig. 5 is a vertical cross-section of the plunger which locates the fasteners in the holding member, taken on the broken line 5-5 in Fig. 2 and showing in elevation a portion of the bell-crank lever and supporting-case and removable seat for the plunger-stop. Fig. 6 is a view in side elevation of the guide-block for the dies and fasteners detached. Fig. 7 is a top end view of the same. Fig. 8 is a front elevation of the same. Figs. 9, 10, and 11 are respectively side, front, and top views of the setting-dies and die-supporting block. Figs. 12 and 13 are respectively side and front elevations of a block which is adjustably con-

nected with the die-supporting block and adapted to be engaged by the main actuating-lever of the machine. Fig. 14 is a right and left screw-threaded link for connecting the blocks shown in Figs. 9 and 12. Fig. 15 is a section taken on the broken line 15-15 in Fig. 2, showing the fulcrum of the actuating-lever and the adjustable bearing-blocks which support such fulcrum. Fig. 16 is a bottom plan view of the tubular holding member detached. Fig. 17 is a vertical cross-section of such member, taken on the broken line 17-17 in Fig. 16 and showing a button with one of the wide fasteners inserted in the button-eye seated in the holding member. Fig. 18 is a similar section taken on the broken line 18-18 in Fig. 16, showing the seating-springs without a button and fastener. Fig. 19 is a longitudinal horizontal section of the holding member, taken on the broken line 19-19 in Fig. 18, showing the inclined portions of the springs in plan. Fig. 20 is a cross-section of a detachable supply-chute and chute-supporting mechanism, taken on the broken line 20-20 in Fig. 2 with the chute in position for use. Fig. 21 is a similar view of a smaller detachable supply-chute and chute-supporting mechanism for the same. Fig. 22 is a top plan or end view of the saucer-shaped setting-die for the wider fastener. Fig. 23 is a vertical section of the same, taken on the broken line 23-23 in Fig. 22. Fig. 24 is a side elevation of a portion of the holding member supporting a fastener and a sectional view of one of the wires forming the saucer-shaped die in engagement with a prong of such fastener. The last three figures are drawn upon an enlarged scale. Fig. 25 is a horizontal section of the setting-dies and adjustable setting-die guide with the inclosing case, taken on the broken line 25-25 in Fig. 2. Fig. 26 is a sectional view showing a button secured to a piece of fabric by a narrow fastener set by my improved machine by turning the fastener-prongs outwardly. Fig. 27 is a similar view showing the button secured by a wider fastener set by my improved machine by turning the fastener-prongs inwardly.

My improved machine comprises a stationary supply-chute containing a raceway for the buttons and fasteners pendent from the button-eyes, a setting member having setting-

dies movable in a stationary guide-support or platform, a holding member movable to and fro between the supply-chute and the setting member, a movable plunger for transferring the buttons and pendent fasteners from the supply-chute into the holding member, seating them therein, and finally expelling them therefrom, and novel mechanism for operating the several parts to automatically feed and successively set upon fabric different kinds of fasteners inserted in the eyes of the buttons.

Referring to the drawings, A is the shell or case, adapted to contain the operating mechanism and having its lower extremity in the form of a cylindrical tube screw-threaded exteriorly to fit the interiorly-threaded end of a hollow standard A', containing the treadle-link A² and retracting-spring S. The spring 20 is secured at its lower end to the link and at its upper end to the case at S'.

B is a stationary supply-chute fixed to the upper portion of the case and provided with a longitudinal slot B', adapted to receive the eye of a button while the button is being fed along the chute. The chute is provided on its under side with a groove or channel B² for the fastener, pendent from the eye of the button.

C is the setting member, having one or more setting-dies of any known form.

The holding member D is fixed upon one arm of a bell-crank lever D', supported upon the journals D², having end bearings in the case-walls.

One side of the case is a removable cover A³, which may be secured to the main case by screws adapted to fit the threaded holes A⁵ in the case and corresponding holes in the cover. 40 The holding member is provided with a slot D³, extending longitudinally of the member and open at both ends to form an open race-way for the buttons and pendent fasteners. The inner open end of such slot is adapted to 45 register with the slot in the supply-chute when the holding member is in an elevated position, as shown in Fig. 1. When such slots register, buttons with pendent fasteners can be easily fed in any known manner from the 50 chute into the holding member to a position for the pendent fastener to engage and be set by the setting-die when the members are operated. The holding member is operated by 55 means of the actuating-lever E, fulcrumed or pivoted at E' and provided at one end with a follower-roller E², adapted to alternately engage and follow the cam-surfaces D⁴ D⁵, one upon each arm of the bell-crank lever. Power is applied to the actuating-lever through the 60 link A², connected with a treadle and retracting-spring. The treadle is not shown in the drawings, as any known form of motor may be employed to operate the machine. When the holding member is in the position shown 65 in Fig. 1, with its slot registering with the slot in the supply-chute, the cam-surface on the lower arm of the bell-crank lever extends

across the path of the follower-roller in a position to be engaged by such roller when the actuating-lever is operated and forced downward to the position shown in Fig. 2. The movement thus imparted to the bell-crank lever is sufficient to bring the holding member into coöperation with the setting member to set the fastener, as will be hereinafter more 70 fully explained. Such movement also brings the cam-surface on the upper arm of the bell-crank lever across the path of the follower-roller in a position to be engaged by the roller when the actuating-lever is operated in an 80 upward direction. The upward movement of the actuating-lever forces the several parts into the position shown in Fig. 1. For introducing a button and its pendent fastener from the supply-chute into the holding member 85 and locating them in the latter I provide a plunger F, reciprocatory in a slideway F', formed in the bell-crank lever. The plunger is located directly beneath the supply-chute and moves in the same vertical plane with 90 the slots in the supply-chute and holding member. The plunger-slideway may have a stationary support or be formed in the movable lever which supports the holding member, as shown. In either case the reciprocating 95 movements of the plunger are so timed and directed as to cause the head or end of the plunger which engages with the fasteners to move along the groove B², formed in the lower side of the supply-chute when the holding member is in alinement with the supply-chute, as shown in Fig. 1. By imparting to the plunger longitudinally-reciprocating movements of the required amplitude when the holding member and supply-chute register 100 with each other a button and pendent fastener can be transferred from the chute to any 105 desired point in the slot of the holding member. Such reciprocating movements may be imparted to the plunger by hand or in any known manner. As a preferred means for operating the plunger I provide a cam-lever 110 F², fulcrumed upon the case at F³. This lever is provided with a cam groove or slot F⁴, adapted to receive an actuating-follower 115 F⁵, fixed upon the actuating-lever E, which may be a projection of the roller-axle, as shown, or any known form of follower. The lever is also provided with a cam groove or slot F⁶, adapted to receive a follower F⁷, fixed 120 upon the plunger. The follower may be a stud projecting from a slide-block F⁸, secured to the plunger and adapted to slide in a slot or slideway F⁹, opening from the plunger-slideway in the bell-crank lever. The vibratory 125 movements of the actuating-lever E thus impart vibratory movements to the cam-lever, and the vibratory movements of the latter impart reciprocating movements to the plunger. The cam-groove F⁴ is so shaped 130 that the cam-lever and the plunger are actuated only while the bell-crank lever is in the position shown in Fig. 1, the follower passing along the lower end of the groove with-

out moving the cam-lever and plunger. Consequently reciprocating movements are imparted to the plunger only when the holding member and supply-chute are in alinement, 5 and vibratory movements are imparted to the holding member only when the plunger is at rest from its reciprocating movements.

To insure the accurate location of the button and pendent fastener in the holding member in a position for the fastener to engage and be set by the setting-die, I provide a positive stop to limit the forward movement of the plunger. The projecting rear end of the plunger is screw-threaded and provided with 15 a stop-nut F^{10} , screwed thereon, to form a stop adapted to engage the seat F^{12} , formed upon the bell-crank lever at the rear end of the plunger-slideway and located in the path of the plunger-stop. The nut is easily turned 20 upon the screw-threaded end of the plunger to change its position longitudinally of the plunger, and thereby vary the limit of the forward movement of the head of the plunger. The forward movement of the plunger being 25 induced by the spring S is only limited by the engagement of the stop-nut F^{10} with its seat, as before explained. I am thus able to determine the exact location of the button and fastener in the holding member and 30 properly locate them relatively to the setting-die in the setting member.

When the nut F^{10} has been adjusted to the desired position, it may be locked by means of the screw F^{13} .

35 By having the stop on the plunger itself and the stop-seat on the plunger-support there is no lost motion, such as takes place where levers or other connections of more or less yielding nature intervene, and I am able to 40 secure the greatest possible accuracy, a matter of importance in the use of some kinds of fasteners and setting-dies.

By means of a removable stop-seat G , pivoted upon the plunger-support at G' , I am 45 able to give the fasteners either of two locations or seats in the holding member without changing the adjustment of the stop-nut on the plunger, the distance apart of the fastener-seats being the thickness of the removable 50 stop-seat. By placing the appropriate dies in the setting member opposite such fastener-seats I can use two different kinds of fasteners in the same machine and easily and quickly adapt the machine to the use of either 55 kind of fastener, it only being necessary to remove or insert the removable seat between the stop-nut and its fixed seat to bring the fastener into a position to engage a selected die.

It is obvious that any desired number of 60 removable plunger-stop seats and setting-dies may be employed so long as the dies are arranged in line with the slot in the holding member, so that the plunger can locate a fastener over the appropriate die.

65 When desired, detachable chutes G^3 may be employed to supply buttons and pendent fasteners to the fixed supply-chute, from

which they are carried one at a time to the holding member by the plunger, as before described. The mechanism which I employ to 70 support the detachable chutes in position to register with the fixed chute consists of a clamp-socket G^4 , formed of some yielding material, preferably a strip of sheet metal bent longitudinally into a form approximately U - 75 shaped in cross-section, with the upper portion of the yielding side walls G^5 bent to form grooves adapted to receive and support the sides of the chute G^3 , the resiliency of the metal forcing the side walls toward each other 80 sufficiently to clamp and firmly support the chute. The clamp is secured to the fixed chute B or other support, as by screws G^7 , in position to cause the detachable chute to register with the supply-slot B' in the fixed chute. 85 The strength of the clamp is sufficient to firmly support the chute without interfering with its easy insertion and withdrawal from the clamp. As a means for supporting a smaller detachable chute G^8 , adapted to supply another kind of fastener, I provide a detachable socket-clamp G^9 , similar in cross-sectional form to the fixed clamp, adapted to be inserted in and supported by the fixed clamp in the same manner as a detachable chute is 90 supported by such clamp, as before described. The upper portions of the side walls of the detachable clamp are curved to approximately fit the detachable chute G^8 when inserted therein and support the same in position to register with the fixed chute. 100

To substitute one type of fastener for another type in operating the machine, it is only necessary to change the detachable chutes and remove or insert the removable plunger-stop seat, as before described. 105

Any known form of feeding device may be employed for feeding the buttons and pendent fasteners one at a time to a position in the stationary chute to be engaged by the plunger and forced into the holding member. 110 The end of the fixed chute contiguous to the vibratory holding member may be inclined upwardly, as shown in Fig. 1, to correspond with the inclination of such member and hold 115 the pendent fasteners in the path of the plunger, while the other end of the fixed chute, or the detachable chute which forms a continuation of the same, inclines upwardly in the opposite direction and has a greater degree 120 of inclination to cause the buttons and pendent fasteners to run down the same by gravity. The latter portion of the chute or chutes I term the "gravity-chute" and that portion contiguous to the holding member the "positive-feed" chute, because the buttons cannot 125 be fed along the same by gravity, but must be forced along by some positively-feeding mechanism, such as the plunger.

The gravity-chute and the positive-feed 130 chute are connected by a curved portion B^4 , as shown, to facilitate the transfer of the buttons and fasteners from one incline to the other and also to facilitate the use of my

novel feeding mechanism for positively feeding the buttons one at a time from the gravity-chute across the curved portion into the positive-feed chute in position for the fastener to be engaged by the plunger.

The segment H of the feeding mechanism is rotarily supported by the ears H', fixed upon the supply-chute B, and is provided with a seat or recess H² in its periphery adapted 5 to receive a single button a. The segment is supported above the supply-chute with its axis at right angles to the slot in the chute and so located that when the segment is partially rotated the button-seat in its periphery is moved through an arc intersecting the path of the buttons in the chute. Axial movements are imparted to the segment through the bell-crank lever, a follower-pin H³ in the lever engaging with the walls of the cam-groove H⁴ in the segment when the holding member is moved to and from the setting member. The segment is preferably located 10 directly opposite the curved portion of the supply-chute, and the cam mechanism for operating the segment is so constructed that the movement of the holding member to or from the setting member causes the button-seat to be moved through an approximate quadrant, which movement is sufficient to feed the seated button from the lower end of the gravity-chute across the curved portion and into the positive-feed chute to a position for its pendent fastener to be engaged by the plunger. While the holding member is in the position 15 shown in Fig. 2, the segment remains stationary, with the button-seat opening toward the buttons in the gravity-chute, so that a button fed by gravity down such chute will enter the recess that forms the seat. As the segment turns on its axis, the button-seat, moving through an arc of a circle, intersects the path of the buttons in the gravity-chute and separating the button which entered the seat from the others in the chute carries it 20 forward into the positive-feed chute in position for its eye and the fastener pendent therefrom to be engaged by the plunger, the buttons left in the gravity-chute being held back by the circular periphery of the segment until 25 the seat is returned to receive another button.

As shoe-buttons are variable in size, I prefer to provide a yielding self-adjusting seat. This I accomplish by forming a part of the segment of resilient sheet metal H⁵ arched or indented to form the button-seat. The normal shape and position of the seat is such that it is adapted to receive and carry the smaller buttons, and when larger buttons are fed to the seat it yields sufficiently to receive 30 and carry them one at a time. This novel feeding mechanism is adapted for use independently of the other features of my improved machine as a means for feeding buttons, with or without fasteners attached, 35 along a chute or raceway, the segment being operated in any known manner.

The setting member comprises a guide J

for the dies detachably and adjustably secured to the case, and a plurality of movable setting-dies J' J². The setting-dies are preferably made of steel wire secured in a supporting-block J³ common to each die. The guide is provided with perforations or openings J⁴ and J⁵, adapted to receive and fit the wire dies. The block J³ is adjustably connected with another block J⁶ by means of a link J', screw-threaded at each end to fit screw-threaded apertures in the blocks. The threads on one end of the link may be finer than those on the other end, or the ends may 70 be right and left hand threaded. When desired, the two blocks J³ and J⁶ may be integral with each other, as indicated by dotted lines J⁸ in Fig. 2. The link may be rotated in the blocks by a lever inserted in apertures J⁹ in hub J¹⁰ or in any known manner. The dies are given a vertically-reciprocating movement in the guide by means of the actuating-lever E, the short end of which inserted in the opening J¹² in the die-supporting block 75 alternately engages the upper and lower walls of the opening. The upper and lower walls of the opening are preferably such a distance apart that the actuating-lever does not engage the upper wall to force the dies upward 80 until the cam-follower on the actuating-lever has engaged the lower cam-surface on the bell-crank lever and forced the holding member downward to the position shown in Fig. 2 and driven the fastener down through the 85 interposed fabric into the guide-openings. After the holding member is thus acted upon the actuating-lever moves, on carrying its follower-roller down, the lower cam-surface on the bell-crank lever and forcing the dies upward 90 through their guides to set the fastener on the lower side of the fabric. The lower cam-surface of the bell-crank lever is approximately the arc of a circle having the fulcrum of the actuating-lever as a center, so that the 95 holding member is held against the fabric and enabled to resist the upward thrust of the setting-dies. The forward pair of wires J' form the movable setting-die adapted to set a narrow staple-fastener b by turning the 100 prongs outward. As the holding member drives the staple down through the fabric the prongs are spread apart by the wedge-shaped die J¹³ in the guide and the ends of the prongs forced into the guide-openings J⁴ 105 in a position to be acted upon by the dies J' and set upon the fabric in the usual well-known manner. The fastener-engaging ends of the wires J' are divergently beveled, as 110 shown in Fig. 10, to correspond with the inclines K K on the holding member and facilitate the spreading of the fastener-prongs. The rear set of dies J² is adapted to set a wide 115 staple d by turning the prongs inwardly toward each other. By having the guide stationary and both dies J² movable I am able to drive the straight prongs of the fastener through the fabric before they are bent by 120 the setting-die, thereby making the least pos-

sible cut in the fabric when inserting the fastener-prongs and producing a strong and durable support for the fastener in the fabric. I provide the upper end of each wire forming the die J^2 with a conical recess J^{15} . When the ends of the die so recessed come in contact with the ends of the fastener-prongs, the prongs are forced to the lowest part or center of the recesses, which causes the prongs of all the fasteners to assume a uniform position in the operation of setting.

It frequently happens, even in button-setting machines having a stationary holding member, that the prongs of pendent fasteners do not hang vertically and are not set uniformly. In the use of my improved die if the prongs do not hang in position to strike the centers of the die-wires the centrally-inclined walls of the recesses will serve to direct the prongs into a uniform and proper position, as shown in Fig. 24, the solid lines showing the ends of the prongs in the proper position and the dotted lines indicating a prong inclined with its end in engagement with a side wall of the recess in the end of the setting-die. When desired, the ends of the die may have a shallow groove J^{16} along a straight line connecting the centers of the recesses in the ends of the die-wires to further guide the ends of the prongs as they pass from the recesses and keep the prongs in alinement with each other when set upon the fabric. By turning the screw-link J^7 in the required direction the length of the supporting-block J^3 J^6 can be varied as desired, and by lengthening the block without changing the vibratory movement of the actuating-lever the dies are forced into closer proximity to the holding member to set the fasteners more closely upon the fabric. Such longitudinal adjustment of the connection between the dies and actuating-lever also affords a convenient means for compensating for the wear of parts, if the wear should be sufficient to permit the dies to fall short of fully setting the fasteners upon the fabric. The limit of the downward movement of the holding member toward the setting member can also be varied to accommodate the space between these coöperating members to the thickness of the fabric. Such variation is accomplished by means of the adjustable bearing-blocks A^7 , which are movable in the slideways formed by the guides A^8 on the case-walls. These bearing-blocks support the bearings for the fulerum of the actuating-lever, and each block abuts at its lower or outer end upon an adjusting-screw A^9 , projecting exteriorly of the case through a threaded aperture in the case-wall. The slideways are preferably arranged to permit the bearing-blocks to be moved toward and from the lower cam-surface on the bell-crank lever. To bring the limit of the downward vibratory movement of the holding member nearer to the setting member, it is only necessary to turn the exteriorly-projecting screws A^9 inwardly,

thereby forcing the bearing-blocks and the fulerum of the actuating-lever which they support nearer the lower cam-surface of the bell-crank lever, whereby the cam-follower E^2 on the actuating-lever amplifies the downward movement of the holding member.

When desired, the bell-crank lever may be actuated in one direction by a separate spring to move it from the position shown in Fig. 2 to that shown in Fig. 1, as by the coil-spring A^{10} , inserted between the edge wall of the case and the lower end of the bell-crank lever. The spring is retained in position by the lug D^6 , projecting from the lower end of the lever. The spring A^{10} is preferably strong enough to force the holding member up into alinement with the supply-chute independently of the action of the follower E^2 upon the cam-surface D^4 . The plunger F is thus carried upward into line with the fastener-grooves in the holding member and lower end of the fixed chute before its forward reciprocatory movement begins, thereby insuring full and positive engagement of the plunger with the button eye and fastener to carry the latter from the stationary chute and properly locate them in the holding member. The upward movement of the holding member is limited by a stop A^{12} on the case so located as to stop the holding member in position to properly aline with the stationary chute. The recess D^7 in the bell-crank lever affords space between the follower E^2 and the lever to permit of the free movement of the lever under the influence of the spring A^{10} after the follower reaches the recess. The recess also permits of the free movement of the lever when the follower alone actuates the lever by alternately engaging its cam-surfaces. The holding member on the upper arm of the bell-crank lever may be of any known suitable form, but I prefer to make use of a detachable tube D , having an open slot D^3 , extending the whole length of the tube to form the raceway for the button-eyes. D^8 is the groove forming the raceway for the yokes of the fasteners. The narrow fasteners b when set upon the fabric are forced by the die-wires J' upon the anvil-inclines K . Just back of these inclines I have shown cross-grooves or recesses K' , one on each side of the raceway, which form the seat for the wider fastener d . The holding and setting members are so located relatively to each other that the seat K' is opposite the die J^2 , which turns the prongs of the fastener inward to set them upon the fabric. The fasteners are located in their respective seats by the plunger, as before explained, in which position they are held up firmly against their seats by the seating-springs P , bearing up against the lower side of the buttons. The form of the two styles of fastener after they are set upon the fabric is shown in Figs. 26 and 27. The recesses K' are so formed as to approximately fit the shoulders d' of the fastener desired to be set by the machine and

form a seat therefor, while the seats K are inclined outwardly and upwardly from the fastener-groove to bend the prongs b' of the narrow fastener up against the fabric. The 5 length of the yoke or eye b² of the narrow fastener b, which projects above the fabric, depends upon the thickness of the fabric and the depth of the groove D⁸ in the holding member. The deeper the groove the longer 10 will be the eye formed in setting the fastener, and the thicker the fabric the shorter the projecting eye.

To obtain the same length of eyes on fabrics differing in thickness, I provide the holding member with a fastener-groove differing in depth and means for locating the fasteners in the desired part of the groove and the setting-die opposite such part. I have shown 15 in Fig. 24 the forward part of the holding-tube cut away on its lower side at K², so as to make the groove D⁸ more shallow than it is at K, thus forming three separate seats for the fasteners in the same holding member. The fasteners are seated in a selected seat by varying 20 the forward movement of the plunger, and the setting-die is adjustable longitudinally of the groove D⁸, as before explained. In the drawings I have shown the parts adapted for a small movement only of the guide-block 25 and dies longitudinally of the groove D⁸, forming the raceway in the holding member. When desired, a larger space may be provided, the case and cover being cut back, as indicated by dotted line g. (Shown in Fig. 2.) 30 By having the supporting-arm of the bell-crank lever grooved or channeled to receive and fit the upper part of the detachable holding member a single screw K³ is sufficient to hold the member firmly in position, as shown, 35 and I am thus able to easily and quickly remove such holding member and substitute therefor another member having fastener-seats differing in form and arrangement, the groove in the supporting-arm adjusting and 40 retaining the member in its proper position to receive the fasteners from the supply-chute and present them to the setting-dies. The 45 seating-springs P are preferably formed by striking from plane sheet-steel by suitable dies blanks having a body part or shank P' with edge wings or springs P. The shank is bent into a tubular form adapted to fit the interior of the holding-tube and bring the 50 springs into a position approximately parallel with and contiguous to each other. The shank is preferably perforated to receive the end of the screw K³, by which the tube is secured to its support on the end of the bell-crank lever. 55

It is obvious that the guide J may be integral with the case A; but by making the 60 same detachable and adjustable I am able to easily change the form or kind of setting-dies and guide or to change their location relatively to the holding member, either to bring 65 the same die into coöperation with different fastener-seats in the holding member by mov-

ing the dies longitudinally of the raceway D⁸ or to move the die laterally of such raceway to secure the proper adjustment after assembling the parts of the machine in the process 70 of manufacture. As a preferred means of adjustably attaching the guide I provide its front side with the inclines e, adapted to be engaged with the adjusting-screws e', inserted in screw-threaded apertures in the case. The 75 guide-block is also provided with a screw-threaded aperture e³, adapted to receive the screw e². This screw is inserted through an elongated aperture, (indicated by the dotted lines e⁴ in Figs. 3 and 25,) so that its head 80 bears upon the outside of the case and draws the guide-block against the screws e'. By moving both screws e' in or out and securing the block in engagement with them by means of the screw e² I am able to secure an adjustment of the guide and dies longitudinally of the raceway in the holding member. By moving one of the screws e' in farther than the other the inclines on the guide-block will 85 force the guide over toward such other screw, thereby affording a lateral adjustment of the guide, the guide being held in its adjusted position by the screw e², the latter screw moving laterally with the guide-block.

What I claim as new, and desire to secure 95 by Letters Patent, is—

1. In a button-setting machine, the combination with a setting member, and a stationary, slotted supply-chute mounted upon a rigid part of the frame, of a holding member 10 movable to and fro between the setting member and supply-chute and provided with a slot open at both ends, adapted to register with the slot in the chute and receive therefrom a button with its pendent fastener, a 105 plunger movable longitudinally of the slots in the chute and holding member for the purpose of feeding from the chute buttons with pendent fasteners, locating the buttons in, and discharging them from, the holding member, and means substantially as described for operating the several parts, substantially as 110 described.

2. In a button-setting machine, the combination with a bell-crank lever having cam-surfaces, and a holding member secured to the lever, of an actuating-lever fulcrumed intermediately of its ends, a cam-follower upon one arm of the actuating-lever engageable with the cam-surfaces on the bell-crank lever, 115 a setting member consisting of a guide or support and a setting-die movable in such support, mechanism for connecting the setting-die and the other arm of the actuating-lever, 120 and means for operating the actuating-lever, 125 substantially as described.

3. In a button-setting machine, the combination with a setting member, and a stationary supply-chute, of a holding member movable to and fro between the setting member 130 and supply-chute, a bell-crank lever for operating the holding member, having a cam-

surface on each of its arms; and a follower-recess D' between its cam-surfaces, a cam-follower adapted to alternately engage the cam-surfaces on the lever, and means for actuating the cam-follower, substantially as described.

5. In a button-setting machine, the combination with a slotted holding member, a plunger movable to and fro along the slot in such member for locating fasteners pendent from buttons in the holding member, and means for imparting to-and-fro movements to the plunger, of a stop-seat, and stop on the plunger, the stop and seat being adjustable relatively to each other, substantially as described.

6. In a button-setting machine, the combination with a holding member having a plurality of fastener-seats located successively along a common supply-groove, of a fastener-locating plunger common to all the seats, and an adjustable stop for limiting the plunger movement, substantially as described.

7. In a button-setting machine, the combination with a slotted holding member having a plurality of fastener-seats and a supply-groove common to such seats, along which groove the seats are successively located, of a setting member having a plurality of setting-dies coöperative with the fastener-seats respectively, and a plunger movable longitudinally of the supply-groove and common to all the seats for locating a fastener pendent from a button in a predetermined seat, substantially as described.

8. In a button-setting machine, the combination with a slotted supply-chute, of a slotted holding member registering therewith and having a plurality of fastener-seats and a supply-groove common to such seats, of a setting member having a plurality of setting-dies coöperative with the fastener-seats respectively, a plunger movable longitudinally of the supply-groove for locating a fastener pendent from a button in a predetermined seat, means for communicating to-and-fro movements to the plunger, and an adjustable stop for limiting the plunger movement, substantially as described.

9. In a button-setting machine, and in combination, a slotted holding member, a slotted chute registering with the holding member, a setting member having a pair of setting-dies arranged in alinement with the slot in the holding member, a locating-plunger movable longitudinally of the slot in the holding member, a stop on the plunger, a fixed seat in the path of the plunger-stop, a removable seat interposed between the fixed seat and the plunger-stop, and means for operating the plunger, substantially as described.

10. In a button-setting machine having a fixed button-supply chute, a holding member movable to and from the chute and means for operating the holding member, the combination with an axially-movable feeding-segment

having a fixed support and a yielding button-seat in its periphery adapted to receive buttons one at a time, of a cam connection between the segment and movable holding member for moving such yielding seat through an arc intersecting the button-supply path, substantially as described.

11. In a button-setting machine, a slotted holding member having a plurality of fastener-seats and setting-surfaces on its underside, and provided with a supply-groove common to such seats and setting-surfaces, the seats being successively located in the groove and differing from each other in depth relatively to the setting-surfaces, substantially as described.

12. In a button-setting machine, a slotted holding member having a plurality of fastener-seats and a supply-groove common to such seats, the seats being successively located along such groove and differing from each other in organized form, whereby they are respectively adapted to seat fasteners of different predetermined types, substantially as described.

13. In a button-setting machine, the combination with a slotted holding member, of a setting-die, and a guide for the die, the die and the guide being adjustable transversely of the slot in the holding member, and means for holding the die and guide in adjustment, substantially as described.

14. In a button-setting machine having a plurality of button-fastener seats in the supply-groove of the holding member, a setting-die and mechanism substantially as described for adjusting the die longitudinally of such supply-groove, substantially as described.

15. In a button-setting machine, a holding member consisting of a tube slotted longitudinally at its bottom, and a tubular member within the slotted tube consisting of a single piece of sheet metal having its body portion bent to approximately fit the interior of the slotted tube, and its longitudinal edge portions cut from the body part along its front end and upwardly inclined along the opposite sides of the tube-slot, substantially as described.

16. In a button-setting machine, a setting-die consisting of a pair of steel wires having their fastener-engaging ends divergently beveled, substantially as described.

17. In a button-setting machine, the combination with a setting member, a stationary supply-chute, a holding member movable to and fro between the setting member and supply-chute, and a stop to limit the upward movement of the holding member, of a bell-crank lever for operating the holding member having a cam-surface, a cam-follower adapted to engage the cam-surface for actuating the bell-crank lever to move the holding member toward the setting member, means for actuating the cam-follower, and a retracting spring engaging the bell-crank lever to move

the holding member from the setting member to the supply - chute, substantially as described.

17. In a button-setting machine, the combination with a stationary guide for the setting die, and a stationary supply-chute, of a holding member provided with a slot open at both ends movable to and fro between the chute and guide, a setting - die movable in such

guide, and means for alternately actuating the holding member and die, substantially as described.

In testimony whereof I have hereunto set my hand this 29th day of April, 1892.

GEO. A. MOSHER.
